G. W. WACKER

RADIO RECEIVING APPARATUS

Filed Aug. 17, 1923

George W. Wacker *INVENTOR*

BY
William S. Gluck
ATTORNEY

UNITED STATES PATENT OFFICE.

GEORGE W. WACKER, OF NORTH BERGEN, NEW JERSEY, ASSIGNOR TO PAL RADIO COMPANY, OF NORTH BERGEN, NEW JERSEY, A CORPORATION OF NEW JERSEY.

RADIO RECEIVING APPARATUS.

Application filed August 17, 1923. Serial No. 657,906.

My present invention relates generally to a radio receiving apparatus and more particularly to one employing a rectifier of the crystal detector type.

5 Among the more important objects of my invention are: the provision in a radio receiving apparatus of a tuning coil made up of two connected but spaced sections; the provision in a radio receiving apparatus 10 having a tuning coil made up of spaced but connected sections, of a tuning member supported in the space between two of such sections; the provision with a tuning coil made up of spaced but connected sections of a tuning 15 member arranged to act as a buzzer when in position between two spaced sections; the provision in a tuning apparatus of an arrangement whereby the minimum tuning is at all times maintained; the provision in a 20 radio receiving apparatus of a new and improved tuning arrangement; the provision in a radio receiving apparatus of an arrangement for supporting a rectifying crystal so as to permit of its quick emplacement and 25 replacement; the provision in a radio receiving apparatus and a container therefor of an arrangement whereby the rectifying member can be discharged from the apparatus directly through the container without 30 removing the apparatus from the container; the provision with a container, of a receiving apparatus arranged to be removed therefrom and replaced as a unit; the provision generally of a new and improved receiving 35 apparatus and hook up.

For the attainment of these objects and such other objects as will appear or be pointed out hereinafter, I have illustrated one embodiment of my invention in the drawings wherein:

Figure 1 is a top view of my apparatus with the cover in open position;

Figure 2 is a view thereof in side elevation;

45 Figure 3 is a view taken in line 3-3 of Figure 2 looking down in the direction of the arrows;

Figure 4 is a vertical section taken on line 4-4 of Figure 3 also looking in the direction of the arrows;

50 Figure 5 is a section on line 5-5 of Figure 4 the arrows indicating the direction in which the section is taken; and

Figure 6 is a diagrammatic showing of my hook up.

55

Upon viewing the various figures of the drawing it will be observed that my invention includes generally a container 10 and a unit filler 11.

60

The container 10 may be of any desired or preferred construction and is provided with a top closure 12 to be held in a closed position in any desired manner as by the fastening means 13 and 14.

65

This unit filler 11 comprises generally the block 15 made of an insulating material such as wood and of a length and width so as to fit conveniently within the container 10 and yet permit of its ready removal therefrom. This block 15 is preferably cut away on its 70 upper surface as shown at 16 in Figure 4; this cut away being shouldered as shown at 17 so as to provide the stepped arrangement shown.

75

A conducting wire 18 is wound upon this block between the shoulders 19 and 20, the resulting coil 18 having two of its adjacent turns spaced a substantial distance apart to provide the space 21 (see Figure 3) the function of which will be pointed out 80 shortly.

85

The wire 18 wound about the block 15, as described, forms the tuning coil of a radio receiving apparatus and for tuning purposes there is provided a lever or contact finger 22 fixed to the post 23 for pivotal movement therewith. This post 23 is carried from a face-plate 24, made preferably of an insulated material such as fibre, the post 23 being provided at its upper end with the insulating knob 25 which has its lower end passing through the block 15. The face-plate 24 is secured in position on block 15 by means of the posts 26, 27, 28, 29 each of which is headed at one end 30' and threaded at the other end, the threaded end being each engaged by the clamping nut 30 to serve not only for securing the face-plate 24 in position on the block 15 but serving also as binding means for the electrical conductors as will now be pointed out.

90

Upon viewing Figures 1, 3 and 5 it will be observed that the block 15 has an opening 31 cut therethrough centrally along and spaced from one side thereof and extending into said opening are the bent up ends 32

100

105

and 33 of members 34 and 35 the former being secured in position in any desired or preferred manner as by a small nail or brad, and the latter being held in electrical contact with the post 29; and for this purpose it is illustrated in Figure 5, as clamped in position between the head of the screw 29 and the block 15. A crystal of any desired or preferred character is received within the opening 31 and is held in such opening by the spring fingers 32 and 33 for purposes that will shortly be pointed out. The opening 31 may be radially enlarged as at 33' in which enlargement is received the spring finger 33 whose gripping action will thus be increased.

An electrical conducting contact member 36, preferably L shaped, is supported from the nut 37 carried by the post 28, the depending leg 36 of the contact member 36 being arranged to contact with rectifying crystal 39 held in the opening 31 as described above. This crystal is of a type which will act as a rectifier in the presence of electrical waves at radio frequency. Upon viewing Figure 5 it will be observed that the block 15 is provided with a groove 40 along one of its side faces through which passes a wire conductor 41 having one of its ends in electrical contact with the post 28 and its other end in electrical contact with the post 27, preferably by being affixed to a metal plate 42 carried by and in contact with the post 27. Upon viewing Figure 4 it will be further observed that a spring member 43 is carried by the post 26 and has its free end sprung upwardly so as to cause it to contact with and press upwardly upon the lower end of the post 23. This spring member 43 thus serves not only as a conductor to place the posts 26 in electrical contact with the tuning coil through the members 22, 23 but also as a retarding means to prevent overthrow of the post 23 and the lever 22 when the knob 25 is operated and to maintain a set or predetermined tuning position. As will be further observed upon viewing Figure 2 the post 27 is connected electrically with one end of the tuning coil 18 by means of the wire conductor 45.

I show my hook-up in Figure 6, and as will be understood upon viewing this figure, I employ a conductively coupled circuit. The antennæ circuit passes from the antennæ 50 to the lead 51, through the slide 52 to the coil 53 and then to the ground by the leads 54 and 54'. The detector circuit passes from the contact member 55 to the lead 56 to the lead 54, coil 53, slide 52 leads 57, 58 ear phones 59 lead 60 to the crystal rectifier 61.

Upon viewing Figure 1 in which a top plan view of a face-plate 24 can be obtained it will be observed that this face-plate has marked upon it the words Ground, Phone,

etc., to assist in hooking up the set as intended. It will be further observed that the post 23 has attached to it above the face-plate the pointer 48 which cooperates with the indications 49 on the face-plate so as to indicate the extent of tuning employed.

The post 27 is grounded in any desired or preferred manner as by being wired to a radiator or a water pipe and the post 26 is attached to or connected with the antennæ. This completes the antennæ circuit from the antennæ to the post 26 from the post 26 to and through the spring member 43 to the post 23 lever 22, tuning coil 18, lead 45 post 27 to the ground. Phones are attached to the post 26 and 29 to complete the detector circuit which passes from the tuner 18-22 to the lead wire 45 post 27 plate 42 conducting wire 41 post 28 contact member 36 crystal member 39, post 29, ear phones then back to the tuning apparatus.

When it is desired to tune in for receiving purposes the apparatus is first connected up, as already set forth above, and the knob 25 turned by hand to cause the downturned outer end of the lever 22 to sweep across the coil 18 so as to tune in more or less of the coil. This movement of the lever 22 to the left in Figure 3 is limited by the shoulder 17, thus always keeping a predetermined minimum portion of the tuning coil in circuit. The movement of the lever 22 in the opposite direction is limited by the shoulder at the other end. When the tuning member 22 is in the position shown in Figure 2 i. e. in the space 21 between the portions of the coil and out of contact with the coils it serves as a buzzer.

Having thus described my invention and illustrated its use, what I claim as new and desire to secure by Letters Patent is the following:

1. In a device of the character described, a tuning apparatus including spaced coils, a rotatable member positioned in the space between the coils, means extending from one end of said member for tuning the coil, and a conductor spring pressed into contact with the other end.

2. In a device of the character described, a tuning apparatus comprising an insulating block having one face thereof cut away, spaced tuning coils wound about the block to position certain conductors thereof in said cut away portion a member passing through and movably positioned in the block between the coils, and means on said member for tuning the coil.

3. In a tuning apparatus of the character described, a supporting block having a pair of opposite parallel faces, one of said faces having a transverse recess whose bottom presents a substantially flat surface, a tuning coil helically wound about the block in a

manner which disposes a portion thereof along said flat surface, and a tuning element mounted in said block and arranged to be adjusted over said surface.

5 4. In a tuning apparatus of the character described, a supporting block having a pair of opposite parallel faces, one of said faces having a transverse recess whose bottom presents a substantially flat surface, a tuning 10 coil helically wound about the block in a manner which disposes a portion thereof along said flat surface, and a tuning element mounted in said block and arranged to be adjusted over said surface, said tuning element 15 comprising a contact finger movable over said surface.

5. In a tuning apparatus of the character described, a supporting block having a pair 20 of opposite parallel faces, one of said faces having a transverse recess whose bottom presents a substantially flat surface, a tuning coil helically wound about the block in a manner which disposes a portion thereof along said flat surface, and a tuning element 25 mounted in said block and arranged to be adjusted over said surface, said tuning element comprising a contact finger in said recess and arranged for movement over the portion of the coil disposed therein.

30 6. In a tuning apparatus of the character described, a supporting block having a pair of opposite parallel faces, one of said faces having a transverse recess whose bottom presents a substantially flat surface, a tuning

coil helically wound about the block in a 35 manner which disposes a portion thereof along said flat surface, and a tuning element mounted in said block and arranged to be adjusted over said surface, said tuning element comprising a contact finger in said 40 recess and arranged for movement over the portion of the coil disposed therein, said finger being pivotally mounted at one end thereof and arranged to permit movement at the other end in an arcuate path between limits 45 defined by the side walls of the recess.

7. In a tuning apparatus of the character described, a substantially flat supporting block having a mid-portion reduced in thickness, a tuning coil helically wound about 50 said mid-portion whereby at least one portion of the coil will lie along a substantially flat surface, and a tuning element mounted in said block and comprising a contact finger movable in a plane parallel to said surface and arranged to be adjusted over said 55 surface.

8. In a tuning apparatus of the character described, an insulating block having one 60 face thereof cut away to provide a recess having a substantially flat base, a tuning coil wound about the block to position a portion thereof in said cut-away portion and in conformity with said base and tuning means movably mounted in said recess. 65

In testimony whereof I have hereunto signed my name.

GEORGE W. WACKER.
